UNITED STATES PATENT OFFICE.

WILLIAM F. SHYLER, OF MEADVILLE, PENNSYLVANIA.

PARCEL-DELIVERY SYSTEM.

Application filed May 24, 1924. Serial No. 715,736.

To all whom it may concern:

Be it known that I, WILLIAM F. SHYLER, a citizen of the United States, residing at Meadville, in the county of Crawford and State of Pennsylvania, have invented certain new and useful Improvements in Parcel-Delivery Systems, of which the following is a specification.

This invention relates to an improved parcel delivery system, which is intended for transcontinental use, the same being especially but not necessarily intended for delivering mail and parcel post packages.

More specifically speaking, what I aim to do is to provide an electrically driven carrier, which is adapted to be suspended from a stationary track, connecting two or more cities or various distant points.

One feature of the invention is to so design the carrier that it will be free from air resistance, during its travel.

Another feature of the invention is to provide improved means of guarding the track, current supply wire, and protection means for the carrier against destruction from exposure to the elements.

A further feature and resultant advantage favoring the present invention is accomplished from the use of an exceedingly rigid and stable suspension device, such as will assure perfect alignment of the supporting rail to, in turn, insure free and unobstructed travel of the carrier thereover.

It is also my aim to provide a suitable and novel transferring device for installation in the system at a predetermined point, for readily transferring a carrier from one rail to the other, so that the direction of travel may be reversed.

Other structural features and advantages derived therefrom will become apparent from the following description and drawing.

In the accompanying drawing, forming a part of this specification, and in which like numerals are employed to designate like part throughout the same:

Figure 1 designates a small section of the suspension device, showing the manner in which the carrier cooperates therewith, the weather shield being shown in section.

Figure 2 is an enlarged cross section taken through the extension device, between two supporting posts.

Figure 3 is a side elevation, showing a

section of the complete suspension device, the carrier being removed.

Figure 4 is a top plan view of a section of the two-rail track.

Figure 5 is an enlarged detail sectional view of the electric motor drive.

Figure 6 is a detail perspective view of an inverted cable bridge.

Figure 7 is a detail view of the turn table or transfer device, used at a terminal.

Referring now to the drawings in detail, it will be seen that the carrier is generally referred to by the reference character 1. While this carrier may be of any suitable construction, it is preferably in the form of a hollow aluminum body, which, in practice, will be about six feet in length. The carrier is fashioned, so that in external appearance it simulates a dirigible, this design being preferred to insure rapid travel and to reduce air resistance. The carrier is supported from one of the extension rails of an elevated track 3. At its front, the connection between the carrier and the rail, is provided through the medium of a swivelled carrying bracket 4.

In practice, roller bearings may be interposed between the bracket and carrier, to permit free turning of the latter around curves in the track. At its rear end (see Figure 5), the carrier is provided on its top with a suitable integral extension 5, which has its free upper end fashioned to form a guard. In this guard, a traction roller 6 is journaled. The shaft of this roller carries a pinion 7, with which an idler 8 meshes, the latter receiving a rotary motion from the driving pinion 9, of the electric motor 10. It is through the medium of this structure that the carrier

is rapidly propelled along the track. The motor 10 may be supported within the carrier, in any appropriate manner, such as, for instance, in the manner shown. It is thus completely housed and protected from the elements. To facilitate the desired traction grip of the roller with the rail, the latter is formed at circumferentially spaced points with rubber inserts 11. In order to obtain current for driving the motor, I utilize a trolley wire 12, which is supported above the rail (see Figure 2). A trolley

13 is pivoted on one side of the carrier, and at its free end it carries a current collecting shoe 14, which rides beneath the trolley wire 12. Suitable wiring, (not shown) is em-

ployed for conducting the current from the trolley to the motor.

By again directing attention to the track 3 it will be seen that suitable transverse and 5 diagonal braces 15 are employed for properly spacing the rails and for securing rigidity of structure. When, by directing attention to Figure 2, it will be seen that predetermined ones of the transverse braces 10 serve as supports for vertically disposed brackets 16, which may, if desired, be made integral therewith, by soldering or otherwise. These brackets in the same constitute supports for a semi-circular or arcuate 15 weather shield 17. Intermediate their ends, the brackets are formed with oppositely disposed arms 18 and these serve to support the aforesaid trolley wires 12. The wires may be attached to the arms in any appropriate 20 way. As seen in Figure 2, the shield is of a width to extend over and beyond the trolley wires and the rails of the track. Hence, the shield serves in a great measure to protect these details from destruction by direct 25 exposure to the elements.

For the purpose of suspending the tracks and cooperating details in elevated position, I use appropriate posts 19, which may be disposed at desired longitudinally spaced 30 points. In practice, these posts will preferably be formed of concrete. The posts in turn, support brackets 20, having upstanding portions 21, on the upper ends of which are the transversely spaced lugs 22. It is 35 to be noted that portions of the upper edge of part 21, extend outwardly beyond the lugs, and these portions constitute seats, upon which the rails of the track are seated. The rails bear against the lugs 22 and are 40 held by beads against lateral displacement. To act in conjunction with the lugs 22, I provide adjustable cables 26, between each pair of posts, these cables being anchored at 45 their opposite ends to the brackets 20, by eye bolts or their equivalents. By preference, each cable is provided with a turn buckle 24, for the purpose of taking up slack in the cable, to render the latter extremely 50 taut, at all times. To place additional stress upon the cable, I use small bridges 25, of the type seen in Figure 6, the depending leg of each bridge being notched in its free end to receive the intermediate portion of the cable. It is with this structure that the intermediate portion of each unit of the track 55 between the pairs of posts is braced.

As before intimated, I provide suitable devices at each terminal, to transfer the carrier from one track to the other. While 60 these devices could be of any suitable construction, I prefer to design them in the manner seen in Figure 7. Reference being had to this figure, it will be seen that a depending track section 26 is swivelly connected with the car 27, movable on a supplement-

tal rail 28. It is, of course, understood that while the view under consideration shows the track section 26 comparatively small, it is of a width equal to that of the main track 3, and the rails thereof are disposed in alignment with the rails of the latter. When the carrier, is received upon the rail of the detail 26, the latter is rotated upon its pivot to transfer the carrier from the "incoming rail" to the "outgoing rail." 75

In practice, the carrier is filled with parcels through the side door, in which it is equipped, and is rolled from the turn table at one terminal to the desired rail of the track. When the trolley pole is swung up 80 to the position shown in Figure 1, the shoe which it carries engages the under side of the current supply wire. The electric system which I use is analogous to that used by present day street railways, that is, a single trolley feed wire and ground rail system. When the current is on, the carrier will travel at a high speed along the track from one terminal to the other. Although I have not shown it, I prefer to use suitable means 85 for stopping the travel of the carrier at predetermined points along the track, for instance, a magnetic brake may be installed upon the armature of the aforesaid motor, and this brake applied when the carrier or conveyor approaches its destination. This could be accomplished by utilizing a "dead portion" in the trolley wire. Since the 90 brake means constitutes no part of the present invention, no further description thereof 95 is deemed necessary, and furthermore, it is believed that the foregoing description, when taken in connection with the drawings, will suffice to enable the reader to obtain a clear comprehension of the invention. 100 For this reason, a more lengthly description is deemed unnecessary. 105

While I have shown and described a specific embodiment of the invention, I wish it to be understood that changes coming within 110 the scope of the subjoined claims may be resorted to, if desired or necessary.

Before completing the description, I would call attention to the fact that the before mentioned bracket 21 on the supporting post, of necessity be constructed in the approximate shape shown, to permit free passage of the carrier, it being understood that the carriers on the two rails are intended to move in opposite directions. 115

I claim:

1. In a device of the class described, a track comprising a pair of parallel transversely spaced rails, transverse braces arranged between said rails, uprights rising from certain of said braces, said uprights being equipped with oppositely disposed arms extending over the rails of said tracks, wires connected to the outer ends of said arms, and an arcuate shield mounted on the 125 130

upper ends of said uprights, the edges of said shields extending outwardly beyond the rails of said track.

2. In a device of the class described, a support, brackets carried by and extending laterally outwardly from said support, said brackets being provided with vertically disposed portions spaced outwardly from said support, the upper end of said vertical portion of the bracket being equipped with transversely spaced lugs, said lugs being spaced inwardly from the edges of said vertical portions to provide rail seats, and a track supported from the vertical portions of said brackets, the rails of said track engaging said seats and said lugs.

3. In a device of the class described, a

pair of supporting posts arranged at longitudinally spaced points, brackets carried by said posts and extending laterally outward, a track having its rails extending transversely across the upper portions of said brackets, a weather shield supported above the rails of said track, a bridge extending transversely across the intermediate portion of said track and having a depending leg, and an adjustable cable stretched between said brackets and anchored at its opposite ends to the latter, the intermediate portion of said cable extending across said bridge.

In testimony whereof I affix my signature.

WILLIAM F. SHYLER.
